PHOTOGRAPHIC PLATE CHANGING MEANS

Filed June 26, 1922

FIG. 1.

Inventor:
Johann Wilhelm
Ludomici
by Kunthauer
Atty.

UNITED STATES PATENT OFFICE.

JOHANN WILHELM LUDOWICI, OF MUNICH, GERMANY.

PHOTOGRAPHIC PLATE-CHANGING MEANS.

Application filed June 26, 1922, Serial No. 571,035, and in Germany July 2, 1921.

My invention has reference to magazine cameras and particularly to magazine cameras for aircraft. It is an object of my invention to improve the usual spring- or gravity-actuated devices for exchanging an exposed plate against an unexposed one. To this end I provide a positive control for exchanging the plates. In this manner, the influence of gravity and friction on the operation of the device is eliminated and the magazine will operate reliably in any position.

A further important feature of my invention is that the positive means for exchanging the plates relieve the plate at the bottom of the pile of the weight of the plates above it and the capacity of the magazine is no longer limited by considerations of weight.

In the drawings affixed to this specification and forming part thereof two forms of a magazine embodying my invention are illustrated diagrammatically by way of example.

Figs. 1 and 2 are an elevation and a plan view, respectively, of a magazine with the front and top plates removed, and showing screw spindles for displacing the plates in parallel to the optical axis of the camera.

1 is the casing of the magazine and 2, 3, 4, 5 and 6, 7, 8, 9 are two sets of vertical screw spindles four of which are arranged along the two transverse edges of the two piles 10, 10. The ends of the spindles are carried in horizontal braces of the casing 1. The plates of each pile are inserted in the threads of the spindles, the plates in the front pile supported by the spindles 2, 3, 4 and 5 being ready for exposure to the lens which is in line with the centre of this pile, and the plates supported in the rear pile by the spindles 6, 7, 8 and 9 are partly exposed and partly stored for exposure in the front pile.

11 is a crank on a vertical shaft 12 projecting from the top plate of the casing 1. Rotation is imparted to the spindles 2, etc., through a bevel gear on the shaft 12 of the crank 11 which meshes with a gear 14 on a horizontal shaft 15 supported in one of

the side plates of the casing 1 and a bracket depending from its top. 16 is a disc on the shaft 15 and 17 is a Maltese cross on a shaft 18 which extends in parallel to the shaft 15. 19 and 20 are helical gears at both ends of the shaft 18, and 21 and 22 are pinions on two horizontal shafts 23 and 24 which extend at right angles below the shafts 15 and 18. Helical pinions 25, 26, 27, 28, 29 and 30 are arranged on these shafts in addition to the pinions 21, 22 and meshing with gears 31, 32, 33, 34, 35, 36, 37 and 39 at the ends of the spindles 2, etc. When the crank 11 is rotated, the shaft 15 rotates with it. Its rotation is transferred to the shaft 18 at predetermined intervals through the medium of the Maltese cross 18 and this intermittent rotation is transmitted in turn to the spindles 2, etc. A bevel pinion 39 is keyed on the shaft 15 and meshing with a pinion 40 on the upper end of a vertical shaft 41. 42 is another bevel pinion at the lower end of the shaft 41 which meshes with a bevel pinion on the horizontal shaft 44 carried in opposite walls of the casing 1. 45 is a bevel pinion on the shaft 44 and 46 is a meshing pinion on a short vertical shaft 47 on which a crank 48 is keyed. This crank cooperates with a frame 50 which is guided on the inner ends of the lower horizontal braces by rollers 55. A similar frame 51 is guided by similar rollers 55' along the inner edges of the upper braces and this frame is adapted to be reciprocated by a crank 49 at the lower end of the shaft 12. The crank pin 48 is connected with a block 54' which is adapted to slide on a diagonal brace 54 of the frame 51. As will appear from Fig. 2 the material of the frame is cut away at both sides of the bracing 54. The lower crank 48 transmits its motion to the lower frame 50 by exactly similar means which are not shown. The connection between the two cranks is such that they will always be at an angle of 180° to each other. When the shaft 12 is rotated the cranks 48 and 49 will displace the frames 50 and 51 in opposite directions.

A pair of spring clips 52 extends upwardly from the lower frame 50 and a simi-

lar pair of clips 53 extends downwardly from the upper frame 51. The clips are arranged at the outer ends of their respective frames and adapted to engage the lower plate of the front pile and the upper plate of the rear pile.

The operation of this camera is as follows:

Suppose that a plate has been exposed in the front pile, in Fig. 1, the crank 11 is rotated so as to move the lower frame 50 forward into the position illustrated in Fig. 2 in which the clips at its front end engage the front edge of the exposed plate. The 15 clips are springy or provided with yielding hooks so that they do not interfere when the frame 50 advances. On further rotation of the crank, the frame 50 is reversed and takes the exposed plate to the rear pile, placing it in the lowest groove of the four spindles $\frac{1}{2}$ of that pile. At the same time the frame 51 is advanced by its crank 49 and places an unexposed plate from the rear pile into the grooves of its four spindles $\frac{2}{3}$ at the 25 top. When the plates have been exchanged in this manner the shaft 15 is rotated by the Maltese cross 17 and all spindles are rotated with it so that the plates in the front pile are raised and the plates in the rear pile 30 are lowered for the lead of the spindles. In this manner, an unexposed plate is placed in front of the lens at the base of the front pile and another unexposed plate is added to the front pile at its top from the top of 35 the rear pile, which has received the exposed plate from the front pile at its base. There are always twelve plates in each pile and after each exposure the exposed plate is withdrawn and replaced by the unexposed 40 plate above it, and the vacant space at the top of the front pile is filled with another plate from the rear pile. This is continued until all 24 plates have been exposed.

I claim:

45 1. In a magazine camera, a magazine for a supply of unexposed plates and a magazine for the reception of exposed plates from said supply, each magazine comprising mechanism for holding and shifting the plates in spaced relation to each other, mechanism for exchanging unexposed against exposed plates between said magazines, a drive for operating said exchanging mechanism, and a connection operatively connected with said drive for intermittently operating said holding and shifting mechanism during the operation of said exchanging mechanism.

60 2. In a magazine camera, a magazine for a supply of unexposed plates and a magazine for the reception of exposed plates from said supply, each magazine comprising mechanism having projections for holding and shifting the plates in spaced relation to each other, mechanism for exchanging un-

exposed against exposed plates between said magazines, a drive for operating said exchanging mechanism, and a connection operatively connected with said drive for intermittently operating said holding and shifting mechanism during the operation of said exchanging mechanism.

65 3. In a magazine camera, a magazine for a supply of unexposed plates and a magazine for the reception of exposed plates from said supply, each magazine comprising mechanism having threaded spindles adapted to engage the edges of the plates between their threads, mechanism for rotating said threaded spindles, mechanism for exchanging unexposed against exposed plates between said magazines, a drive for operating said exchanging mechanism, and a connection operatively connected with said drive for intermittently operating said spindle-rotating mechanism during the operation of said exchanging mechanism.

70 4. In a magazine camera, a magazine for a supply of unexposed plates and a magazine for the reception of exposed plates from said supply, each magazine comprising mechanism for holding and shifting the plates in spaced relation to each other, mechanism having means for engaging the ends of the plates and adapted to exchange unexposed against exposed plates between said magazines, a drive for operating said exchanging mechanism, and a connection operatively connected with said drive for intermittently operating said holding and shifting mechanism during the operation of said exchanging mechanism.

75 5. In a magazine camera, a magazine for a supply of unexposed plates and a magazine for the reception of exposed plates from said supply, each magazine comprising mechanism for holding and shifting the plates in spaced relation to each other, mechanism having spring catches for engaging the ends of the plates and adapted to exchange unexposed against exposed plates between said magazines, a drive for operating said exchanging mechanism, and a connection operatively connected with said drive for intermittently operating said holding and shifting mechanism during the operation of said exchanging mechanism.

80 6. In a magazine camera, a magazine for a supply of unexposed plates and a magazine for the reception of exposed plates from said supply, each magazine comprising mechanism for holding and shifting the plates in spaced relation to each other, mechanism for exchanging unexposed against exposed plates between said magazines, a crank for operating said exchanging mechanism, and a connection operatively connected with said crank for intermittently operating said holding and shifting mechanism during the operation of said exchanging mechanism.

7. In a magazine camera, a magazine for a supply of unexposed plates and a magazine for the reception of exposed plates from said supply, each magazine comprising mechanism for holding and shifting the plates in spaced relation to each other, mechanism for exchanging unexposed against exposed plates between said magazines, a drive for operating said exchanging mechanism, and a Maltese cross for intermittently operating said holding and shifting mechanism during the operation of said exchanging mechanism. 10
In testimony whereof I affix my signature.
JOHANN WILHELM LUDOWICI.
